(57) CLAIM

The ornamental design for a cosmetic brush handle, as shown and described.

DESCRIPTION

FIG. 1 is a perspective view of an exemplary embodiment of a new design for a cosmetic brush handle;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The bristle portion of the cosmetic brush shown in broken lines is to show environment only and does not form part of the claimed design.

1 Claim, 5 Drawing Sheets
